CLOTHESLINE POST

Watkins Walter Wilkinson and Carl K. Smith,
Corpus Christi, Tex.

Application October 10, 1945, Serial No. 621,536

3 Claims. (Cl. 189—31.5)

1

This invention relates to means for supporting clotheslines, one of the objects being to provide a post of novel construction which, when once set in place, will not shift out of position when subjected to excessive strains such as heavy loads and pressures exerted by strong winds.

A further object is to provide a post which can be easily erected and thereafter firmly anchored to the ground.

A still further object is to provide a post of this character which can be set up without the necessity of digging holes or driving the posts into the ground.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

In the accompanying drawing the preferred forms of the invention have been shown.

In said drawing

Figure 1 is a front elevation of the post set up for use.

Figure 2 is a side elevation thereof.

Figure 3 is an enlarged section on line 3—3, Fig. 1.

Referring to the figures by characters of reference, 1 designates an angular base plate having a depending flange 2 constituting a lip adapted to be forcibly inserted into the ground by the act of setting up the posts. This base has spaced openings the locations of which have been indicated generally at 3 and said openings are adapted to receive hook-like tongues 4 extending downwardly from pipes 5 which preferably are parallel and can be joined by an interposed stiffening strip 6 of zig-zag configuration and welded or otherwise securely attached to the pipes where it contacts therewith.

These joined pipes constitute the main body of the post and the upper ends of the two pipes are adapted to receive short stems 7 extending downwardly from a pipe 8 constituting a cross-head. This latter pipe can be formed of one or more sections and can be reinforced in the direction of its length by means of a truss consisting of a rod 9 secured at its ends to the ends of the pipe 8 and provided at intermediate points with spacing members 10 joined to the pipe 8.

To the members 10 can be attached hooks 11 carried by turn buckles 12 which, in turn, are

joined by guy wires 13 or similar devices to an anchoring stake 14. This stake has a helical blade 15 forming a screw whereby the stake can easily be forced into the ground by turning it as pressure is exerted thereagainst.

It is to be understood that two of these posts are to be used where one or more clotheslines L are to be erected. The clotheslines are cut to required lengths and fastened at their ends to the cross-heads 8. One of the posts is then set on end so that the flange or lip 2 on the base thereof will bear upon the surface of the ground. The other post is similarly set up at such a point that when the lines L are drawn taut the posts will diverge upwardly. The stakes 14 associated with the respective posts are forced into the ground beyond the space between the posts and by means of the turn buckles 12 the guys 13 can be tightened so as to draw the lines L taut and maintain them in such condition.

When the post is not in use the guys can be loosened by means of the turn buckles and unhooked from the members 10. The posts can be lowered to the ground, the stakes 14 withdrawn from the ground and the cross-heads lifted from engagement with the pipe 5. Thus the posts can be compactly stored until such time as it might be desired to set them up for use.

What is claimed is:

30. 1. A clothesline post including a base, said base comprising a flat relatively elongated post-supporting portion and a ground-engaging lip depending from one edge thereof, the post-supporting portion being formed with spaced openings, fixedly connected pipes upstanding from the base, tongues on the lower ends of the pipes movably engaged in said openings, a cross-head bearing on the pipes, stems integral with the cross-head snugly seated in the pipes, said 35 cross-head constituting means for engagement by a clothesline, an anchoring stake having a screw blade, and guys detachably connected to the cross-head and converging to the anchoring means, each of said guys including an adjusting element.

2. A clothesline post including a flat, relatively elongated base plate rectangular in form, a lip integral with the base plate and depending at a right angle from one longitudinal edge thereof, said base plate having spaced tongue-engaging openings, pipes, fixedly connected from end to end, extending upwardly from the base plate in spaced parallel relation, hook-like tongues on the lower ends of the pipes movably received in said tongue-engaging openings, whereby the pipes

may be extended from the base plate obliquely, said pipes being open at their other ends, a clothesline-engaging cross-head bearing on the pipes, spaced stems on the cross-head snugly and removably received in the upper ends of the pipes, an anchoring stake including a helical blade, and adjustable guy ropes detachably connected to the anchoring stake and to the cross-head.

3. A clothesline support embodying opposed clothesline posts, each post including a flat relatively elongated rectangular base plate positioned transversely of the line of direction of a clothesline supported between the posts, a rectangular lip depending from a longitudinal edge of the base plate, pipes, fixedly connected together from end to end in parallel spaced relation, swingably and detachably mounted on the base, a clothesline-engaging cross-head bearing on the pipes, an anchoring stake including a screw blade, and adjustable guys connecting the stake and cross-head, said anchoring stake being threadable into the ground at a distance beyond the space be-

tween the opposed posts, whereby upon insertion of the stakes into the ground, the opposed posts will be swung upon the base plates into a position at an oblique angle to the base plates.
